UNITED STATES PATENT OFFICE.

EMIL A. NELSON, OF DETROIT, MICHIGAN, ASSIGNOR, BY MESNE ASSIGNMENTS, TO STEEL WHEEL CORPORATION, OF LANSING, MICHIGAN, A CORPORATION OF MICHIGAN.

METHOD OF FORMING WHEEL DISKS.

Original application filed March 17, 1927, Serial No. 176,112. Divided and this application filed September 28, 1927. Serial No. 222,433.

The invention relates to the manufacture of disk wheels and more particularly to the production of fashioned dished disks of radially tapering cross section, and is a division of my copending application, Serial No. 176,112 filed March 17, 1927.

In the present state of the art disks of this character have been manufactured by various methods. In certain of these methods a flat blank of uniform cross section is rolled or machined while still in the flat to produce the desired radial taper and is subsequently pressed to the desired form. Other methods produce the tapered blank in different ways but none are adapted to fashion the disk to its final form simultaneously with the taper producing operation.

It is the object of the present invention to simplify the operation and to speed up production first by devising a disk of such form that it may be tapered and fashioned in one operation; and second, by a novel method of performing these operations.

For purposes of exemplification, rather than limitation, a preferred embodiment of a machine adapted to practicing the invention is set forth in the following description and in the accompanying drawings wherein

Fig. 1 is a sectional elevation of a machine for carrying out my improved method showing the fashioned disk resting thereon;

Fig. 2 is partially a horizontal section through the bearing axis with moving parts in top plan; and

Fig. 3 is a horizontal section on line 3—3 of Fig. 1.

Fig. 4 is an isometric view of one member of the two-part adjustable bed plate.

Disk wheels of the single disk type are of a great variety of forms but are all dished along simple or compound curved lines to produce the necessary stability and, in some instances, to impart a pleasing design. The production of the taper in the blank by rolling requires an expensive construction of machine, it being necessary that the forming rolls should travel radially while exerting very heavy pressure.

It is one of the features of my improvement that the taper portion of the blank is of a radial arcuate form so that it may be developed by a roll or other forming tool

traveling about a center. Another feature is that the center of movement of the forming tool is slightly eccentric to the arc of the 55 table or platen thereby automatically producing a radially outward taper.

As illustrated, a machine for carrying out my improved method comprises a base 11 having mounted thereon a supporting frame 60 12 for a revoluble table or platen 13, the latter being connected to a rotatable spindle 14 actuated by beveled gears 15 from any suitable source of power. Rising from the bed are columns 16 which carry at their upper 65 ends the cross head 17. On the under side of this cross head are arranged the obliquely extending ways 18 for adjustable journal bearings 19 and trunnions or journals 20 engaging the said bearings. These trunnions are attached to the heads 21 having bearings 22 for revoluble forming rolls 23. The axes of these rolls are oblique so that the rolls revolve in oblique planes converging toward a point in the axis of the spindle 14. 75

The rolls 23 are also disposed in such relation to the table or platen 13 that when the heads 21 are rocked upon the journals 20 said rolls will trace an arcuate path adjacent said table. 80

Arranged in any suitable location, but as shown beneath the bed 11, is a hydraulic cylinder 24. The piston rod 25 of this cylinder is connected with a pair of levers 26, 27 fulcrumed on opposite sides of the bed 85 and extending transversely thereof. The free ends of these levers 26, 27 are connected by rods 28, 29 with the members 21 by means of the brackets 30 and pins 31, the arrangement being such that the movement of the piston 90 will impart simultaneous rocking movements to the members 21 causing the rolls 23 simultaneously to travel through arcuate paths from the center to the periphery of the table or platen 13. 95

Interposed between the frame 12 and the platen 13 is a two part bed plate 32, 33, having cooperating spiral cam faces 32_a and 33_a, the bed member 32, being preferably stationary and the member 33 angularly adjustable about the neck 12_a of the frame, whereby to effect vertical adjustment of the platen, which is carried by rolls 34. 100

With the construction as thus far de-

scribed the method of forming a tapered fashioned disk is as follows:

The platen 13, which is preferably removably splined on the spindle 14, is of a form corresponding to that which is to be imparted to one face of the disk. The bearings 19 are disposed so that the axes of the trunnions 20 are slightly eccentric to the arcuate contour of the platen in radial cross section. The eccentricity is just sufficient to produce a gradual tapering space between the path of the roll and the contour of the table, this corresponding to the desired taper in the disk.

15 When the machine is properly adjusted a circular blank such as 35 is placed upon the platen 13 and is secured thereto, conveniently by engaging a headed pin 36 which is pressed down upon the platen by a 20 hydraulically operated plunger 37. The central portion of the platen surrounding this pin and within the arcuate portions thereof, is flat so that the blank is firmly clamped to the platen and will be revolved 25 therewith.

In operation, rotary motion being imparted to the gears 15 and spindle 14, hydraulic pressure is applied by the piston rod 25 to the levers 26 and 27 which, through 30 the rods 28 and 29, rock the members 21 and the forming rolls 23 carried thereby. These will first press upon the blank 30 at a radial distance from the center of said blank slightly greater than the radius of 35 the flat portion of the platen and will then traverse an arcuate path, gradually spinning

the metal of the blank into conformity to the platen.

At the completion of the operation the blank will be tapered in radial cross section 40 and will also be expanded in diameter to a corresponding degree. This operation is preferably performed upon comparatively soft metal which during the spinning operation, is hardened and greatly increased 45 in strength.

The taper fashioned disk produced by the method just described may be attached to the wheel rim in any suitable manner as, for instance, by pressing the peripheral portion 50 of the disk laterally to form an attachment flange.

I claim:

1. The method of forming dished disks of tapering radial cross section, comprising 55 the mounting of a flat blank on a fashioned platen, spinning said platen and blank to conform the latter to the former and simultaneously to progressively thin and radially expand the same.

2. The method of forming dished disks of tapering radial cross section, comprising the mounting of a flat blank upon a revoluble platen having a portion arcuate in radial contour, spinning said platen and blank to 65 conform a portion of the latter to said arcuate contour, and simultaneously progressively thinning and radially expanding the same.

In testimony whereof, I have hereunto 70 subscribed my name.

EMIL A. NELSON.
